UNITED STATES PATENT OFFICE

HORACE C. ALLEN, OF MERCHANTVILLE, NEW JERSEY, ASSIGNOR TO GENERAL ELECTRIC COMPANY, A CORPORATION OF NEW YORK

LOCAL-DISTANT SWITCH FOR SUPERHETERODYNE RECEIVERS

Application filed October 7, 1930. Serial No. 487,049.

The present invention relates to superheterodyne receiving apparatus and the like and more particularly it relates to a local-distant switch for receiving apparatus of that character.

The problem of protecting a receiving circuit from excessive voltages generated in a receiving antenna by local or high power transmitting stations may be met by providing a switch in the antenna circuit for disconnecting the antenna when receiving such stations. In connection with a sensitive superheterodyne receiving apparatus, this simple protective arrangement has been found to be not entirely satisfactory or effective, and it is the object of the present invention to provide an improved local-distant switch and circuit therefor which is particularly adapted to protect a superheterodyne receiving circuit from excessive voltages generated in the receiving antenna and to permit such apparatus to function properly when operating to receive any high power or local station without signal distortion.

The invention will be better understood from the following description when taken in connection with the accompanying drawings and its scope will be pointed out in the appended claims.

In the drawings, Fig. 1 is a schematic wiring diagram of a portion of a superheterodyne receiver provided with a local-distant switch embodying the invention, and Figs. 2 and 3 are modifications of the local-distant switch of Fig. 1.

Referring to Fig. 1, 5 is the first detector of a superheterodyne receiver provided with an input circuit 6 connected to a source of radio frequency signals 7 through a tuned input transformer 8. The detector is provided with an output or anode circuit 9 which is connected to the primary 10 of a tuned input transformer 11 for an intermediate frequency amplifier (not shown). Sources of potential for the operation of the detector are indicated at 12 and 13. The detector may be of any suitable type and accordingly further description thereof is believed to be unnecessary.

Interposed between the output circuit and

the primary 10 of the transformer 11 is a local-distant switch 14 which may be moved to a position 15 to provide a direct connection with the transformer primary 10 through a compensating condenser 16, and which may be moved to an alternate position 17 to provide a connection with a tap point or tap 18 on a resistor 19-20 which is connected in shunt with the output circuit.

The condenser 16, which is connected between the resistor 19-20 and the transformer 11, is a compensating device in connection with the output circuit for limiting the load provided by resistor 19-20 on the primary of transformer 11. The condenser 16 prevents the load provided by the resistor from materially affecting the frequency response range or characteristic of the transformer 11, which in a superheterodyne receiver is set for a certain predetermined intermediate frequency for use in connection with an intermediate frequency amplifier.

The resistor 19-20 is provided with the tap 18 at a point such that the ratio between the resistance values of section 20 and of the whole resistor 19-20 is in the same relation as the sensitivity ratios desired for local and distant reception. In the present example, resistor section 20 may be substantially 2000 ohms, while resistor section 19 may be substantially 40000 ohms, and the compensating device or condenser 16 may have a value of substantially 25 micromicrofarads.

It will be seen that when the local-distant switch 14 is moved to the local position 17, the resistor section 20 is connected in shunt with the output circuit, while the resistor section 19 and the compensating condenser 16 are connected in series with the output circuit and with the primary 10 of transformer 11. Resistor section 19 is therefore in circuit with the primary 10 for limiting the transfer of energy to the transformer.

When the local-distant switch is moved to the distant position 15 it will be seen that the output circuit is connected directly with the transformer primary 10 through the compensating device 16 while the load resistance at 19-20 is connected in shunt with the output circuit. It has been found that by plac-

ing the local-distant control switch in the position indicated, between the first detector and the input transformer or coupling device for the intermediate frequency amplifier, an effective control of the signal strength applied to the receiver is obtained under widely differing conditions of operation. The switching arrangement as shown and described has the advantage that while it operates to change the energy transfer between the detector and the intermediate frequency amplifier by changing the load on the output circuit of the detector, it does not appreciably affect the load placed upon the primary of the transformer or coupling device 11, whereby its frequency characteristic is not appreciably changed by the switching operations.

Referring now to Figs. 2 and 3, the local-distant switching means, provided in Fig. 1 between lines 21 and 22, are shown with slight modifications. In Fig. 2, an additional circuit compensating device or condenser is indicated at 23. This condenser is connected in the output circuit in such a manner that it is short circuited by the local-distant switch 14 when the latter is moved to its distant position 15, and is included in circuit when the local-distant switch is moved to its local position 17.

The function of the compensating device 23 is to provide in connection with the primary 10 of the transformer 11, a capacity load which compensates for the loss of the detector capacity load. In the present example the capacity of condenser 23 may be substantially 16 micromicrofarads. When the local-distant switch 14 is moved to its local position 17, the compensating condenser 23 is interposed in circuit between the load resistor 19-20 and the detector.

In Fig. 3, the circuit is the same as in Fig. 2 except that the resistor section 19 is omitted along with the compensating condenser or device 16. This arrangement provides for a direct connection between the detector and the primary of transformer 11 when the local-distant switch is moved to its distant position, and maintains the compensating condenser 23 in circuit when the local-distant switch is moved to the local position. In a circuit of this character, the resistance section 20 may be reduced to a value less than 2000 ohms or may be increased to a value as high as 8000 ohms.

It will be noted that in the modification shown in this figure, as well as the preceding figure, the output circuit of the detector is completed through the resistor 19-20 or 20 alone. Accordingly the resistance values should not be high enough to greatly reduce the anode voltage on the detector in connection with a detector of the type indicated in the present example.

It is pointed out that the relative values of the resistor sections 19-20, in connection

with Figs. 1 and 2, may be varied to provide differing ratios for local and distant signal strength. The signal strength for distant reception may also be varied by varying the value of the compensating or coupling condenser 16, although the values as given have been found to be satisfactory.

What I claim as new and desire to secure by Letters Patent of the United States, is:

1. In a superheterodyne receiving apparatus, the combination of a signal detector having an output circuit, an amplifier coupling device connected with said output circuit, said coupling device having a predetermined frequency response characteristic, switching means connected between said output circuit and the coupling device for changing the energy transfer from said output circuit to said device, and means arranged to be connected in circuit with said coupling device and said output circuit by said switching means for preventing a change in the frequency response characteristic of said coupling device when said switching means is operated.

2. In a superheterodyne receiving apparatus, the combination of a signal detector having an output circuit, an amplifier coupling device connected with said output circuit, said coupling device having a predetermined frequency characteristic, a resistor, a switch for connecting said resistor in circuit with said coupling device and said detector for changing the output of the latter, and a condenser in circuit with said coupling device and resistor for maintaining the load on said coupling device substantially constant.

3. In a radio receiving apparatus, the combination with a signal detector having an output circuit, of a coupling device having a predetermined frequency response range connected with said output circuit to receive signal energy therefrom, switching means interposed in said output circuit for changing the load thereon and compensating means connected in said output circuit for preventing said load changes from affecting the frequency response of said coupling device.

4. In a radio receiving apparatus, the combination with a signal detector having an output circuit, of a transformer having a predetermined frequency response range connected with said output circuit to receive signal energy therefrom, a resistor, a condenser, circuit connections for said resistor and condenser with said output circuit and the transformer, and switching means arranged to change said circuit connections of said resistor to limit the transfer of energy from said output circuit to said transformer and with said condenser to prevent a change of the frequency response range of said transformer when the circuit connections are changed.

5. In a superheterodyne radio receiving ap-

paratus, a detector having an output circuit, an input transformer for an intermediate frequency amplifier connected with said output circuit, a resistor connected in shunt to said 5 output circuit, said resistor being provided with a tap, a condenser connected in said output circuit between the resistor and the transformer, a second condenser connected in the output circuit between the resistor and the de- 10 tector, and a switching means connected with said output circuit resistor and last named condenser which is movable to one position to short circuit said condenser and to another position to remove said short circuit and to 15 connect the detector output circuit to said tap on the resistor.

6. In a superheterodyne radio receiving apparatus, a detector having an output circuit, an input transformer for an intermediate 20 frequency amplifier connected with said output circuit, a resistor, a condenser, and switching means for said output circuit connected with said resistor and said condenser and arranged to connect said resistor in shunt to said output circuit and said condenser in series therewith between said resistor and said input transformer.

7. In a superheterodyne radio receiving apparatus, a detector having an output circuit, 25 an input transformer for an intermediate frequency amplifier connected with said output circuit, a resistor connected in shunt to said output circuit, said resistor being provided with a tap, a condenser connected in said output circuit between the resistor and the transformer, said condenser being proportioned to adjust the load on said transformer to a desired value, a second condenser connected in the output circuit between the 35 resistor and the detector, said condenser having a value such that it compensates for the detector capacity load on the transformer, and a switching means connected with said output circuit resistor and last named con- 40 denser which is movable to one position to short circuit said condenser and to another position to remove said short circuit and to connect the detector output circuit to said tap on the resistor.

50 8. In a superheterodyne receiver, the combination with a detector and a coupling device arranged to receive the signal output therefrom, said device having a certain frequency response characteristic, of a local-dis- 55 tant switch means interposed between said detector and said transformer for changing the signal energy transferred to said transformer, said means including a resistor connected with the output circuit, switching 60 means for changing the connection of said resistor to effect a change of the load on said output circuit, and circuit compensating means in said output circuit for preventing a corresponding change in the load on said 65 transformer, whereby the response character-

istic of the transformer is maintained substantially constant.

In witness whereof, I have hereunto set my hand this second day of October, 1930.

HORACE C. ALLEN.
